United States Patent Office

Des. 220,410
Patented Apr. 6, 1971

220,410

MARKING PEN

James H. Lee and James R. Pauls, Walnut Creek, Calif.,
assignors to Dymo Industries, Inc., Emeryville, Calif.

Original design application May 7, 1968, Ser. No. 11,816,
now Patent No. 217,838, dated June 16, 1970. Divided
and this application Mar. 25, 1970, Ser. No. 22,044

Term of patent 14 years

Int. Cl. D19—06

U.S. Cl. D74—17

FIG. 1 is a front elevational view of a marking pen showing our new design;

FIG. 2 is a side elevational view of the marking pen, both sides having the same appearance;

FIG. 3 is a rear elevational view of the marking pen;
FIG. 4 is a top plan view of the marking pen; and

FIG. 5 is a bottom plan view of the marking pen.
This application is a division of our application Ser. No. D. 11,816, filed May 7, 1968 and now Pat. D. 217,838, granted June 16, 1970.

We claim:

The ornamental design for a marking pen, as shown and described.
